Specification for Design.

Patented July 11, 1916.

Application filed March 17, 1916. Serial No. 84,972. Term of patent 3½ years.

To all whom it may concern:

Be it known that I, ALFRED O'CONNOR, a subject of the King of Great Britain, having declared my intention of becoming a citizen of the United States of America, residing at Northport, county of Suffolk, State of New York, have invented a new, original, and ornamental Design for a Peace-Flag, of which the following is a specification, reference being had to the accompanying drawing, forming part thereof.

The figure is a plan view of a "Peace Flag" showing my new design.

I claim:

The ornamental design for a "Peace Flag" as shown.

ALFRED O'CONNOR.
